UNITED STATES PATENT OFFICE.

DAVID A. BATTS, OF ATLANTA, GEORGIA.

COMBINED SHADE ROLLER AND HOLDING MEANS FOR WINDOWS.

Application filed May 3, 1926. Serial No. 106,398.

This invention relates to a combination shade roller and holding means for windows, and has for its primary object to provide such a dual construction whereby the shade may be supported at various locations with respect to the window frame for permitting light and air to enter above the shade when the upper window is lowered or for permitting the entire sash construction 10 to be shaded by drawing downwardly upon the shade when the roller is supported at the upper end of the frame.

Other objects will become apparent as the nature of the invention is better understood, the same comprising the novel form, combination, and arrangement of parts hereinafter more fully described, shown in the accompanying drawings and claimed.

In the drawings wherein like reference 20 characters indicate corresponding parts throughout the various views:

Figure 1 is a front elevation of a window equipped with my combination shade roller and holding means.

Figure 2 is a fragmentary enlarged outer side elevation of the shade and one of the units of the holding means.

Figure 3 is a detail vertical section taken through Figure 1 for disclosing said unit in 20 inner side elevation, said unit being partly broken away, and certain elements of construction thereof being disclosed in full and dotted line position.

Figure 4 is a detail transverse section taken through the unit disclosed in Figures 2 and 3, and the adjacent end of the shade roller.

Figure 5 is a detail vertical section taken through one end of the shade roller substantially upon the line 5-5 of Figure 2, and looking in the direction toward the right, as per the arrow in said figure.

Figure 6 is a detail fragmentary longitudinal section through the shade roller constructed in accordance with the present invention, and

Figure 7 is a similar view through the opposite end thereof.

Reference will first be had to the shade roller construction more specifically disclosed in Figures 4, 5, 6 and 7. Said construction constitutes the provision of a wooden roller 5 of predetermined length that is formed throughout its length with a bore 6 within which is loosely arranged a

shaft 7, the opposite ends of which extend beyond the ends of the rollers and are flattened at said ends as indicated by the reference character 8 in Figure 4. Upon the ends of the roller 5 are metallic cap plates 60 9 and 10, Figure 6 and 7 respectively. Each cap plate is formed with a bearing sleeve 9' and 10' respectively while the sleeve 10' carries a set screw 11 that is formed at its inner end with a pin for engagement within a circumferential channel 12 in the shaft 7 for preventing longitudinal movement of the same within the bore of the roller.

At one end of the bore 6 within which the shaft 7 is disposed, the same is formed 70 with an enlargement 13, Figure 6, within which is arranged a normally unwound coil spring 14 that surrounds the shaft and that is anchored at one end to the shaft and at the opposite end to the adjacent cap plate 75 9 upon the roller 5.

Pivoted to the cap plate 9 is a hook dog 15, the hooked end of which is adapted for engagement within an opening 16 in the adjacent side of the bearing sleeve 9' in order 80 that said hooked end may engage within a pair of shouldered notches 17 formed upon the shaft 7 within said bearing sleeve, Figures 5 and 6.

Secured to the roller 5 is the usual shade 85 18 which is adapted to be wound thereon, and at this point it may be well to state the shaft 7 of the roller is to be held against rotation by the action of the holding means hereinafter more fully described. When the 90 shade is fully wound upon the roller, a downward pull of the same will release the shade from the roller in order that it may be positioned at the desired point with respect to the sashes as shown in the window construction of Figure 1. To prevent the reverse rotation of the roller upon the shaft, the hook of the dog 15 will engage within either one of the shouldered notches 17 of 95 said shaft. However, if the shade is quickly released, the dog 15 will ride over these shoulders even in the reverse direction, and permit the spring 14 of the roller to unwind which will turn the roller thereon.

Keyed to the bearings 9' and 10' are spur gears 19-19, Figures 4 and 7, that so co-operate with the holding means hereinafter more fully described for permitting of the raising and lowering of the entire roller with respect to the window.

Said holding means constitutes the provision of a pair of units A, and B, disclosed in Figure 1, that are to be located at the inner edges of the side bars of the window frame C, at the upper ends thereof. The length of these units is preferably greater than the length of the upper sash in order that the roller may be moved to position directly in front of the upper end of the lower sash to permit light to enter through the entire area of the upper sash when the same is closed, or to permit air to enter through the opening of the window construction when said upper sash is lowered. Each of the units A and B is of identical construction, and consequently a description of one will suffice for both.

Each unit of the holding means includes an L-shaped bar 20 that is so arranged with respect to the inner side of the adjacent window frame bar as to have the wide side thereof engage the adjacent side of the window frame bar, while the narrow side of the L-bar is at the rear side of the window as clearly disclosed in Figure 2, the outer edge of said narrow side of the L-bar being formed upon its inner face with rack teeth 21, the upper and lower ends of the portions of the L-bar being formed with said rack teeth being in sections 21—21 that are pivoted to the bar as clearly disclosed in Figure 3, said sections being normally maintained in longitudinal alignment with the stationary portion of the toothed side of said bar by reason of spring strips 22—22 that are secured to said pivoted sections and to the stationary portion of the bar.

Upon the lower toothed sections 21 of each unit is a depending strip of metal 23 that extends beneath the L-bar of the unit in order said section may be swung outwardly to the dotted line position disclosed in Figure 3, and there be maintained by reason of a holding plate 24 pivoted to the lower edge of a sheet metal guard plate 25 secured to the front edge of the L-bar 20, Figure 4.

Secured to the strip 23 is one end of a chain 26 that extends through an opening 50 in the lower end of the short side of the L-bar 20, and then extends upwardly and back of said narrow side to a point adjacent the upper end thereof at which point it passes through an opening 27 in the narrow side of the L-bar at which point the chain passes through an opening 27 in the narrow side of said L-bar and thence upwardly through an eye 28 in a bolt 29 that is secured to the upper frame bar of the window frame after which said chain passes inwardly toward the unit and is anchored as at 30 to the end thereof, Figure 3. It will thus be seen that when the lower section 21 is moved outwardly into the dotted line position of Figure 3, a pull will be caused upon the

chain for drawing outwardly upon the upper section 21 as also disclosed in the dotted lines of the same figure, or in a manner and for a purpose hereinafter more fully described.

The wide sides of the L-bars 20 of each unit A and B is formed throughout its length with a channel 31 within which the flattened ends 18 of the roller shaft 7 are mounted for sliding movement. Said channels are backed by a rib 32 that is formed adjacent its upper end with a transverse opening 33 that communicates with said channel 31 and within which slides a locking pin 34 formed upon the inner end of an L-shaped bolt 35 arranged over the outer side of the L-bar 20, the outer end thereof being secured to the upper pivotal section 21 of the narrow side of said L-bar in order that when said section is swung forwardly to the dotted line position of Figure 3, the pin will engage beneath the respective end of the shaft 7 for preventing the dropping of the roller after the teeth carrying sections 21 of the unit have been moved away from the gears 19—19. At this point it may be well to state that the teeth of the gears are adapted for mesh with the teeth of the angle bars in order that a turning of the roller while in mesh with the teeth of the bars of the unit will cause the upper and lower movement of the roller in order that the same may be arranged at any desired position with respect to the window frame. Obviously, when the roller has been moved to a position at the upper ends of the units or at the lower ends thereof and the sections moved outwardly to the dotted line positions of Figure 3, the roller may be rotated in reverse direction for unwinding or winding 105 the shade 18 without the consequent vertical movement of said roller.

Detachable pins 37 are provided for engagement within registering openings in the guard plate 25 and the narrow side of the L-bar 20 at the lower end of each unit for preventing the dropping of the roller from the unit when the lower sections have been moved outwardly to permit of the rotation of the roller without the consequent rising 115 of the same within the unit. These pins are however readily detachable in order that the roller may be removed from the units whenever desired.

It will thus be seen that I have provided a combination shade roller and holding means for windows that is well adapted for all the purposes heretofore designated, even though I have herein shown and described the invention as comprising certain detail structural elements, it is nevertheless to be understood that modifications may be had without affecting the spirit and scope of the appended claim.

Having thus described the invention, what

I claim as new and desire to secure by Letters Patent is:—

In combination with a window shade including a stationary shaft and a shade roller 5 mounted thereon, a pair of guide units arranged vertically upon opposite sides of the window frame and within which the ends of said shaft are mounted for sliding movement, cooperating construction between the 10 units and the roller whereby the shade in its entirety is moved in reverse direction when the roller is turned upon the shaft, means at the opposite ends of the units

whereby the roller may be mounted for turning movement without the consequent movement of the same in reverse directions, said 15 means at the opposite ends of the units being simultaneously operable and means at the opposite ends of the units for preventing the dropping of the shade when said other means 20 are moved to position to permit the rotation of the roller without its movement in reverse direction with respect to the window.

In testimony whereof I affix my signature.

DAVID A. BATTs.
